United States Patent Office

Des. 207,840
Patented June 6, 1967

207,840

CHAIR OR THE LIKE

Miguel Rodrigo, Republica de Chile St. 284, Lima, Peru

Filed Oct. 23, 1965, Ser. No. 87,870

Term of patent 14 years

(Cl. D15—1)

FIG. 1

FIG. 2 is a front view; and

FIG. 3 is a perspective front view.

The essential features of my design reside in those portions shown in full lines on the drawing.

I claim:

The ornamental design for a chair or the like, as shown and described.
